MOTOR AND SUPPORT THEREFOR

Paul Dean Cornelius, Tulsa, Okla., assignor to
 Sullivan Machinery Company, a corporation of
 Massachusetts

Application September 30, 1936, Serial No. 103,253

11 Claims. (Cl. 121—194)

My invention relates to pumping apparatus, and more particularly to pumping apparatus of the type using a fluid pressure operated pumping motor for actuating a pump in a well through a sucker rod line or other mechanical connection. It also relates to supports—particularly to supports for use with wells and well equipment.

In a certain form of oil well pumping system, it is customary to mount a fluid pressure operated motor in line with a well and to connect the moving element of said motor directly with a sucker rod line leading down into the well to the pump therein. In installations of this character, since frequently high speeds of piston movement are used, and since, due to the great depth of some such wells, cylinders of very substantial cross sectional area are employed, it is desirable to provide substantial quantities of operating medium in close juxtaposition to the pumping motor so that substantial variations in pressure may be eliminated; and since very commonly such motors operate single-acting and have their down strokes opposed by a substantial back pressure, it is also desirable to have a volume tank or its equivalent connected to the exhaust from said motor so that exhausting may not be unduly retarded due to small pipe-size. It is also desirable with motors of this character to be able to move them aside, out of line with the well, so that access may be had to the latter more conveniently when it is desired to take up the pump or perform some other operation with respect to the well.

With standard mountings, it has been common to employ a rigidly constructed tower and to suspend flexibly from the top of the tower, or adjacent the top of the latter, a pumping motor cylinder; but as the tower has been rigid, the pumping motor had to be swung to one side, if withdrawal of the pump was desired, and then did not clear completely the space above the well; and separate volume tanks were commonly employed.

It is an object of my invention to provide an improved structure which will permit the meeting of the needs of a pumping outfit of the character described, with great compactness, with freedom from radical variations in pressure, and with the possibility of completely clearing the space above the well. It is another object of my invention to provide an improved support for a pump operating motor, or for any other motor to be used in connection with a well, which will permit the movement of the motor completely out of alignment with and completely out

of the line above the well. It is still another object of my invention to provide an improved structure combining, in the support for a motor used with a well, volume tanks, using the same element for a dual supporting and volume-tank-providing function. It is yet another object of my invention to provide an improved combination of operating motor and support having an improved fluid supply and exhaust system. As motors of the type mentioned may at times be used for drilling functions as well as for pumping functions, it is still another object of my invention to provide an improved arrangement for supporting a motor and supplying operating fluid thereto, which will permit the complete movement of the motor out of line with a hole in the earth in conjunction with which said motor is used. It is a further object to provide an improved adjustable support. Other objects and advantages of the invention will hereinafter appear.

In the accompanying drawings, in which one form which the invention in its various aspects may assume in practice, has been shown for purposes of illustration—

Fig. 1 is a front view of a pumping apparatus in which my invention is incorporated.

Fig. 2 is a side view.

Fig. 3 is a section on the plane of the line 3—3 of Fig. 1, through a distributing valve mechanism.

Fig. 4 is a fragmentary view, on a similar section but on an enlarged scale, showing a portion of the distributing valve mechanism.

Fig. 5 is a view partially in vertical section and partially in side elevation of a pumping motor forming a part of the pumping apparatus shown.

Referring to the drawings, it will be noted that 1 represents a pumping motor and 2 an improved supporting means therefor. The construction of the motor 1 may obviously assume many forms, but herein I have illustrated a pumping motor of the type disclosed in the application of Wade H. Whineman, Serial No. 40,949, now Patent No. 2,184,932, which patent is assigned to the assignee of my present application. This pumping motor includes an upper head 4, a lower head 5, and a cylinder 6. Within the bore 7 of the cylinder a piston 8 is reciprocable. The piston rod 9 of the piston is connected, through a suitable connecting device 10, with a sucker rod 8 leading to any suitable pump, desirably located near the bottom of the well. The heads of the pumping motor are clamped together by side rods 11. The lower cylinder head 5 includes a fluid distribution mechanism, gen-

erally designated 12. This comprises a fluid supply connection 13, to which fluid is conducted through a flexible fluid conductor 14, hereinafter more fully described; a fluid exhaust connection 15, from which fluid is conducted through a flexible connection 16, hereinafter more fully described; and a fluid admission and exhaust passage 17 connected to the lower end of the cylinder 7. Septa 19 and 20 respectively separate the passage 17 from the supply space 13 and the exhaust space 15. A valve chamber forming sleeve 21, ported for communication with passages 13, 15 and 17, is suitably held within a stepped bore 22 formed in the lower head member 5 of the motor. A distributing valve 23 is mounted within the member 21, and comprises an enlarged head 24 movable in a bore 25 in sleeve 21, a cylindrical portion 26 movable in a bore 27 in sleeve 21, a spaced head 28 also movable in the bore 27, and a reduced connecting portion 29. Between the portions 26 and 28 there is formed a groove 30 which is adapted selectively to connect the inlet space 13 with the cylinder passage 17 and to connect said cylinder passage 17 to the exhaust connection 15. The end of the bore 27 remote from the larger bore 25 is continuously connected with the exhaust space 15 through a connection 31. Means for supplying fluid to and venting fluid from the end of the bore 25 remote from the bore 27 is provided, and this construction is best shown in Figs. 4 and 5. The distributing valve 23 carries a check valve element 33 yieldably supported thereon, this element yielding to prevent breakage and to permit the necessary movement of the valve 23, but not yielding under the fluid pressure to which the exposed end thereof may be subjected. In a cap 34 closing the upper end of the bore 25 there is a yieldingly mounted valve 36 having associated therewith passage means 37 so arranged that when the stem 38 of the valve is actuated by the valve 23 and the valve 36 is unseated, fluid may flow between the bore 25 and a passage 39. Valve 33 is adapted to cooperate with a seat 40 surrounding a passage 41. When the valve 33 is remote from its seat 40, flow between the bore 25 and passage 41 is possible. Passage 39 opens into the cylinder bore 7 fairly near the desired upper stroke limit, being designed to have its mouth uncovered by the lower end of the piston substantially at the end of the desired up stroke. Passage 41 opens into the cylinder bore 7 near the lower end of the latter, being uncovered by the upper end of the piston 8 as the latter moves downward, near the lower end of the stroke. Valve 36 also will not be unseated by fluid pressure alone acting directly on it.

The mode of operation of this apparatus will be very readily understood when it is appreciated that the motor back pressure may run anywhere from 50 to 100 pounds, for example; the motor supply pressure from 200 to 300 pounds, for example, and the pressure above the piston 8 in the cylinder bore 7 will be maintained not more than one or two pounds above atmospheric at any time, by means of any suitable vent device 44.

Assume now a position of the parts as shown in Fig. 3, and it will be appreciated that the valve 23 is maintained in fluid-admitting position (the position shown in Fig. 3) due to the fact that the smaller end thereof is subjected to a pressure of perhaps fifty to one hundred pounds, while the larger end thereof is subjected only to substantially atmospheric pressure through the

connection 39, the passages 37 in the valve 36 and the vented upper end of cylinder 7.

The piston 8 therefore moves upwardly, and when it passes above the mouth of passage 41 nothing happens, because this passage is closed by the valve 33. When, however, the lower end of the piston passes above the mouth of the connection 39, cylinder pressure passes through the ports 37 in the valve 36, acts on the larger end area of the valve 23, and throws the valve down to connect passage 17 with exhaust connection 15. When the valve 23 moves to the position shown in Fig. 4, flow through valve 36 is no longer possible, as the latter closes, but flow through passage 41 will then be possible. The pressure above the valve 23 reduces as cylinder pressure falls, but not below cylinder back pressure, and so the valve remains in the position of Fig. 4 because its larger end is subjected to the same pressure as its lower end. The piston 8 moves downward, after valve 23 has been thrown, and when the upper end of the piston 8 passes beneath the mouth of connection 39 nothing happens, because the valve 36 is held so forcibly to its seat that the back pressure within the bore 25 cannot unseat the valve 36. When, however, the piston gets substantially to the bottom of its stroke and its upper end passes below the mouth of passage 41, the pressure in the chamber 25 is vented to atmosphere through the upper end of cylinder 7, and the back pressure acting on the end of the head 28 of the valve will throw the valve again to fluid-admission position. This cycle will continue as long as fluid is supplied to the motor.

With this preliminary understanding of the mode of operation of the motor 1, the construction and beneficial nature of the support or tripod 2 can be more readily understood. Herein it will be observed that the tripod is supported on three foot blocks, which are generally designated 50, 51 and 52. On each of these foot blocks there is suitably held a pivot-providing device or pedestal, these being designated 53, 53' and 53'' and each comprising a pair of spaced plate members 54 having extending between them a pivot element 55.

Each of these members 53, 53' and 53'' supports a tripod leg, and the latter are numbered respectively 56, 57 and 58. Referring first to the leg 56, this is constructed of pipe or tubing and is hollow throughout its ends and is closed at its opposite ends by head members 59 and 60, respectively arranged at the bottom and the top of the member 56 and welded thereto. Each of the head members 59 and 60 has a flange or web portion projecting therefrom, and the lower one of these portions, 61, is pivotally connected to the pivot-providing device 53 by the pivot member 55. The upper one, 62, is pivotally connected to a head or support member 63 arranged at the top of the tripod. The length of the member 56 is fixed. The member 56 constitutes an exhaust chamber and has a connection 64, herein leading back to the intake side of a compressor 65 which supplies air to the pumping motor, when such a system is used. If steam is used, this simply constitutes the return line to a condenser or to a water tank or the like; or may simply exhaust outdoors if that is necessary—desirably, in the latter case, with a certain back pressure maintained upon it by a suitable automatic valve mechanism. The bottom of the member 56 may be drained through a suitable valve-controlled drain connection 66.

The leg 56 is one of a pair of forward legs, and the leg 58 is the other of these forward legs. The construction and mounting of the leg 58 is very similar to that of the leg 56. However, in this case the lower end of the leg is closed off at a slightly higher level than is the case of the leg 56, and the bottom of the leg 58 is provided with a length-adjusting mechanism 66, which may assume any suitable form, but which is herein shown as comprising an elongated threaded member and a series of cooperating nuts adjustably connecting a pivot piece 59' to leg 58. A fluid supply connection 69 opening into the interior of the body of the leg 58 supplies motive fluid to the latter from any suitable source, and an appropriate valve-controlled drain connection 70 is provided near the bottom of the space within the leg 58. The interior of the leg 58 is connected through the flexible tubing 14 to the space 13 within the valve chest of the pumping motor 1; and the flexible connection 16 connects the space 15 within the valve chest of the motor with the interior of the hollow leg 56. Obviously, by adjustment of the mechanism 66 the position of the tripod top may be laterally varied. This will permit the bringing of the central point of the top member 63 into laterally overlying relation with respect to the well. Forward and backward adjustment is also possible, as will now be explained.

The top 63 is provided with a rearwardly projecting arm portion 72, to which the rear leg member 57 is connected. This rear leg member is adjustable and is provided at its lower end with a turnbuckle 74, which is pivotally connected to the pivot-providing device 53'. The upper end of the turnbuckle is connected to a member 15, which forms the outer member of a telescoping joint structure 76, whose upper element is comprised by the long rod portion 77, which makes up the major portion of the length of the leg 57. A quick-releasable connection 78 permits, upon its withdrawal, a telescoping of the part 77 within the part 75, and a rearward tilting of the tripod to the position shown in dotted lines in Fig. 2, which completely clears the space above the well with which this apparatus is adapted to be used.

The head member 63 comprises also a downwardly projecting plate portion 80, to which is pivotally connected, as at 81, a pair of upstanding, perforated ear portions 82 secured to the top head 4 of the pumping motor. Between the ear portions 82, upon a transverse pivot 85, there is mounted a transversely extending arm 86, whose outer ends provide supports 87 for the connection thereto of flexible elements 88. Each of these flexible elements is provided at its lower end with a turnbuckle 89, and these may be connected, through suitable connecting devices 90, with appropriate attachment devices 91 secured in any suitable manner, desirably below ground level, an appropriate framework extending between the pedestal blocks 50 and 52 being one possible method of providing attachment points for the lower ends of the flexible elements 88.

Now referring particularly to the disclosure of Fig. 2, it will be noted that, when the parts are in the full-line position shown, and the tripod is in its position for the support of the pumping motor 1 for pumping operation, the leg member 57 is in tension and the leg members 56 and 58 in compression, and the flexible elements 88 are in tension; and that accordingly, the entire apparatus is in a most stable condition. It will be

noted, moreover, that the pumping motor 1, by reason of its method of suspension, is free to adapt itself to perfect alinement with the well over which it is suspended. Any suitable ladder 92 may be extended upwardly to a platform 93, having appropriate guard railings 94 and in turn supporting a ladder 95 leading up to the top, substantially, of the tripod—to a position adjacent the point of motor suspension. Appropriate braces 96 extending outwardly from the leg elements 56 and 58 cooperate with the ladder 92 in providing a support for the platform.

From the foregoing description, it will be apparent that I have provided an improved tripod or tower mounting for the suspension of a motor 15 for drilling or for pumping a well, and that this tripod is particularly adapted for use with pneumatic or other expansible fluid operated, reciprocating, expansible chamber motors, in that the hollow legs 56 and 58 provide volume tanks in 20 which so much space is provided that great fluctuations in pressure in the operation of the motor may be avoided. It will be observed, moreover, that the tripod or tower mounting is very 25 stable when in use, and yet permits the easy effecting and automatic maintenance of alinement between the axis of the pumping motor and the axis of the well. It will further be noted that merely by slackening the tension of the cables 30 35 40 45 50 55 60 65 70 75 80 85 90 95 100 105 110 115 120 125 130 135 140 145 150 155 160 165 170 175 180 185 190 195 plurality of legs, one of said legs being hollow and providing a volume tank, and means for supplying motive fluid to the interior of said hollow leg and for delivering such fluid from said hollow leg to said motor.

5. 3. In combination, an expansible-chamber motor, a tower mounting therefor including a plurality of hollow legs each providing a volume chamber, means for supplying motive fluid to one of said hollow legs to the interior of the latter, means for discharging fluid from the interior of another of said hollow legs, and means for connecting the interiors of said last mentioned pair of legs respectively with the motor inlet and the motor exhaust.

10. 4. In combination, a motor adapted to exhaust against a substantial back pressure and have a large drop in pressure between its working pressure and its back pressure, and means for supporting said motor during operation including at least one hollow leg providing within the same a volume chamber, means for conducting fluid from said volume chamber, and means for connecting motor exhaust to said volume chamber.

15. 5. In combination, in an apparatus of the character described for pumping wells, a pair of pedestals arranged adjacent to but not in the same vertical plane with the well, and a third pedestal substantially laterally displaced from 20 said first mentioned pedestals, legs pivotally supported by each of said pedestals and having pivotal connections at their upper ends with a top, a pumping motor pivotally suspended by said top and positionable, with all of said legs at one side 25 of a vertical plane including the well axis, in alignment with said well axis, and also out of alignment with said well axis into positions between said pair of pedestals and said third pedestal but parallel to its first mentioned position, 30 when all of said legs remain at the same side of said vertical plane, two of said legs making different angles with a vertical plane passing through their respective pedestals in the different specified positions of said pumping motor.

35. 6. In combination, in an apparatus of the character described for pumping wells, a pair of pedestals arranged adjacent to but not in the same vertical plane with the well, and a third pedestal substantially laterally displaced from 40 said first mentioned pedestals, legs pivotally supported by each of said pedestals and having pivotal connections at their upper ends with a top, a pumping motor pivotally suspended by said top and positionable, with the axes of all of said legs 45 at one side of a vertical plane including the point

5. of suspension of said motor, in alignment with said well axis, and out of alignment with said well axis but parallel to its first mentioned position, when certain of said legs lie at different sides of a parallel plane including the new positions of the point of suspension of said motor.

6. 7. In combination, a driving motor, supporting means for said driving motor including a fluid storage reservoir formed in a supporting element for said motor, means for supplying fluid to said reservoir and for delivering fluid from said reservoir to said motor to operate the latter, said supporting means pivotable to position said motor in vertical alignment with its work or in a vertical position laterally offset from its work.

10. 8. In an apparatus of the character described, a tripod having a motor pivotally supported at its upper end and free to align itself with the axis of its work, and adjustable means acting to maintain one of the legs of said tripod under tension and the remaining legs of said tripod under compression with the axes of the latter legs in a plane deviating only slightly from the motor axis, said adjustable means being adjustable to 20 vary the tension and compression when the legs 25 are in said plane.

9. In combination, an expansible chamber motor, and means for suspending the same in alignment with a well including supporting legs respectively formed to provide line and exhaust fluid volume tanks for said motor and arranged at opposite sides of the latter.

10. 10. In combination, a motor, and supporting means therefor including a pair of supporting legs in compression, adjustable tension means acting in lines lying at opposite sides of a plane including the axes of said supporting legs for placing said supporting legs under compression when said motor is in its work-performing position, and a pivotal support for said motor carried 35 at the top of said legs and constructed to provide for free swinging of said motor relative to each 40 of said legs.

11. 11. In an apparatus of the character described, a tripod having pivotally adjustable legs, 45 at least one of said legs having associated therewith means for adjusting its effective length, a motor pivotally supported at the upper end of said tripod, and adjustable means acting to maintain one of the legs of said tripod under tension and the remaining legs of said tripod under compression, said adjustable means being adjustable to vary the tension and compression for any given pivotal adjustment of said legs.

PAUL DEAN CORNELIUS. 55
